CLAIM

I claim, the ornamental design for a boot, as shown and described.

DESCRIPTION

FIG. 1 is a front view of a boot, showing my new design;
FIG. 2 is a rear view thereof;
FIG. 3 is a right side view thereof;
FIG. 4 is a left side view thereof;
FIG. 5 is a front perspective view thereof;
FIG. 6 is another front perspective view thereof;
FIG. 7 is a rear perspective view thereof;
FIG. 8 is a rear and bottom perspective view thereof;
FIG. 9 is a front and bottom perspective view thereof;
FIG. 10 is a left side and bottom perspective view thereof;
FIG. 11 is a right side and bottom perspective view thereof;
and,
FIG. 12 is another front and bottom perspective view thereof.

The broken lines in the drawings depict portions of the boot that form no part of the claimed design.

1 Claim, 12 Drawing Sheets
